Richard C. Diebenkorn, Atherton, Calif., assignor to Dohrmann Hotel Supply Co., San Francisco,
Calif., a corporation of Nevada

Application June 22, 1951, Serial No. 15,635

Term of patent 14 years

(Cl. D36—8)

To all whom it may concern:

Be it known, that I, Richard C. Diebenkorn, a citizen of the United States, residing at Atherton, in the county of San Mateo and State of California, have invented a new, original, and ornamental Design for a Sundae Glass, of which the following is a specification, reference being had to the accompanying drawing, forming a part thereof.

Referring to the drawing:

Fig. 2 is a top plan view.

I claim:

The ornamental design for a sundae glass, as shown.

RICHARD C. DIEBENKORN.
